UNITED STATES PATENT OFFICE.

CHARLES J. MARTH, OF ST. LOUIS, MISSOURI, ASSIGNOR TO WAYNE MANUFACTURING COMPANY, OF ST. LOUIS, MISSOURI.

GEARING.

1,008,169.

Specification of Letters Patent.

Patented Nov. 7, 1911.

Original application filed May 13, 1910, Serial No. 561,040. Divided and this application filed February 4, 1911. Serial No. 606,625.

To all whom it may concern:

Be it known that I, CHARLES J. MARTH, a citizen of the United States, residing at St. Louis, in the State of Missouri, have invented certain new and useful Improvements in Gearing, of which the following is a specification, reference being had therein to the accompanying drawing.

This invention relates to improvements in gearing, and is a continuation or division of my co-pending application filed May 13th 1910, Serial No. 561,040, (now patent 984,831, dated Feb. 21st 1911) as to the eccentric for actuating the agitator through intermediate mechanism, and as to the specific construction of the eccentric and its co-operating parts.

Referring now to the drawings—Figure 1 is a perspective view of my improved 20 washing machine which embodies the present invention. Fig. 2 is a top plan view of the same. Fig. 3 is a vertical sectional view on the line 3—3 of Fig. 2 the hinged tub cover being shown closed in full lines and 25 fully open in dotted lines. Fig. 4 is a vertical sectional view on the line 4—4 of Fig. 2. Fig. 5 is a detached perspective view of the eccentric, its strap and operating parts, the parts being shown in separated relation.

30 In carrying out the present invention, preferably a horizontally arranged tub 1 is provided, which is supported upon suitable legs 2. The washing and wringing mechanisms are driven, as here shown, by an electric motor 3, of a low horse power, and this motor is supported upon a suitable shelf or bracket 4, which is secured to the legs 2, the motor being located under the tub and out of the way. While an electric motor is 35 shown and described, yet it is to be understood that other forms of motor may be employed for driving the mechanisms. A cover 5, which almost covers the top of the tub 1, is hinged in a manner to be herein- 40 after described. At one edge of the top of the tub a suitable board 6 is attached thereto, and this board supports the driving mechanism which will now be described.

45 At one end of the board 6, a base 7 is provided and at the opposite end of the board is a base 8. Projecting vertically from the base 8 is an arm 9 which carries a bearing 10, and projecting from each end of the base 8 are vertically disposed arms 11, 50 which carry bearings 12. A driving shaft

13 is journaled in the bearings 10 and 12 and this shaft, as shown, extends across but above one edge of the tub 1, and parallel with the inner straight edge of the cover 5. Suitably journaled in the outer end of the 60 base 7, is a suitable combined driving pulley and balance wheel 15, the shaft of which carries a pinion 16, which meshes with a gear 17, the gear being rigidly attached to the shaft 13. A suitable belt 18 passes 65 around the pulley 15 and a small pulley 19 on the shaft of the motor 3.

A vertical shaft 20 is journaled in the cover 5. The inner or lower end of this shaft 20 carries an agitator head 21, to 70 which is attached suitable agitator arms 22. A vertical socket 23 projects from the agitator head 21 and the inner end of the shaft 20 is connected to this socket in any suitable way to permit the agitator to move toward the cover 5 when it is opened, as shown in Fig. 3, and at the same time locked to the socket 23 against independent revolution, whereby the rotation of the shaft 20 causes the agitator 21 to be rotated. As 75 here shown the means consists in having the socket 23 provided with an angular longitudinal opening 24 and the end of the shaft 20 with a correspondingly shaped head 25. The cover 5 is provided with an opening 26 80 to permit the upper end of the socket 23 to pass therewith when the cover is opened, as shown in dotted lines, Fig. 3.

Attached to the outer side of the cover 5, is a suitable housing 27, in which the upper 90 end of the shaft 20 is journaled. Rigidly attached to the upper end of the shaft 20 and within the housing 27, is a gear 28. A reciprocating gear rack 29 moves in the housing 27 and engages the gear 28. When 95 the gear rack 29 is reciprocated, the gear 28 and the agitator 21 are alternately rotated in opposite directions, whereby the agitator agitates the clothes within the tub and this effects the washing thereof in the 100 manner well understood by those skilled in this art.

The means for reciprocating the rack-bar 29 consists of an eccentric 30, around which passes an eccentric strap 31, the strap having a projecting arm or pitman 32, which has its outer end loosely connected with the rack-bar 29 at the point 33.

The eccentric 30 has a flanged bearing 34, which is normally loose upon the shaft 110

13 and that end of the sleeve 34 which is adjacent the bearing 10 is provided with a collar 35 which interlocks with a flange 36, projecting from the bearing 10, whereby the eccentric is held against endwise movement on the shaft 13. The opposite end of the sleeve 34 is adapted to interlock with a clutch 37 that is longitudinally movable on the shaft 13. This clutch and the adjacent 10 end of the sleeve 34 are provided respectively with interlocking means, such, for instance, as a slot and projection 38. The clutch is permitted to have a longitudinal movement on the shaft 13, but is caused to 15 rotate therewith by means of the well-known slot and pin construction 39. A clutch operating lever 40 is intermediately pivoted upon a bracket 41, the inner end of the lever 40 having the usual well-known yoke construction 42, adapted to interlock with a groove 43 made in one end of the clutch 37. The pivotal bolt 44 passes loosely through an opening 45 in the lever 40, and a suitable spring 46 serves to normally hold 20 the handle end of the lever 40 in locked engagement with either of the notches 47 upon the bracket 41. By lifting up on the handle end of the lever 40, it can be disengaged from the notches 47 for the purpose of causing 25 the clutch to either interlock with the sleeve 34 of the eccentric and cause the eccentric to revolve with the shaft 13, or to be disengaged from the sleeve 34 and permit the driving shaft 13 to rotate free within 30 the sleeve and without agitating the eccentric.

The opposite end of the driving shaft 13 from the pulley 15 is adapted to be operatively connected or disconnected from the 35 wringer 48. The mechanism for accomplishing this comprises a beveled gear-wheel 49, which is rigidly attached to the projecting end of the shaft of one of the wringer rolls 50. As here shown, this gear 40 is attached to the lower roll. Located on the shaft 13, at opposite sides of the beveled gear 49 and constantly in mesh therewith are beveled gears 51 and 52. These gears are loose on the shaft 13 and placed between 45 them is a clutch sleeve 53. This clutch sleeve is longitudinally movable on the shaft 13, but is caused to rotate therewith by the well-known slot and pin construction 54. The opposite ends of the clutch 53 are adapt- 50 ed to either interlock with the beveled gears 51 or 52, or to be held out of locking engagement with either of the gears. This is accomplished through the medium of an operating lever 55, which is intermediately 55 pivoted at the point 56 in a manner similar to the lever 40, before described. A yoke 57 is formed on the inner end of the lever 55 and is adapted to engage a groove 58 in the clutch sleeve 53 for the purpose of moving 60 the clutch sleeve, and the lever 55 and

thereby the clutch sleeve 53 is locked in position to hold the clutch sleeve in engagement with either of the beveled gears 51 or 52, or out of engagement with both by engaging the notches 59, the lever 55 being 70 adapted to interlock with either of the notches 59, or be unlocked therefrom in the manner described in respect to the lever 40.

From this description it will be observed that both the washing and the wringing 75 mechanisms can be thrown out of operation while the driving shaft 13 is revolving, or either the washing and the wringing mechanisms can be operated while the other is inoperative, or both can be operated at the 80 same time and the wringer rolls caused to rotate in either direction.

The object of reversing the direction of rotation of the wringer rolls is to permit the clothes to be wrung from the tub into 85 a bluing or rinsing tub located outside of the wringer, the clothes passing over a suitable shelf 60, falling into the rinsing or bluing tub located thereunder, and by reversing the wringer rolls the clothes can be 90 wrung from the bluing or rinsing tub without moving its position, and thus avoiding the necessity of carrying the rinsing or bluing tub with the clothes to the rear of the machine.

The electric cable 61 has one end connected to the motor 3, and the opposite end provided with a well-known socket 62 adapted to be placed in the ordinary electric light socket, and intermediate the socket 62 and 100 the motor a switch 63 is provided for the purpose of having convenient means for turning on and cutting off the current to the motor.

Referring now to the hinged construction 105 for the cover 5, it comprises a hinge which has its pivotal point located in a plane above the cover and at a point inside of the driving shaft 13. This is accomplished by providing the cover hinged plates 64 with upwardly projecting arms 65 and the inwardly projecting arms 66, which project respectively from the arms 9 and 11 of the bases 7 and 8. The outer ends of the arms 65 and 66 are hinged or pivoted together at 110 the point 67. By reason of this elevated hinged construction the cover 5 when open is above and extends outwardly over the driving shaft and its operating mechanism as shown in dotted lines, Fig. 3, which permits access to the tub 1, without and interference by the agitator, and also raises the cover and the agitator in such position as to leave free access to the wringer. When the cover 5 is in this raised position, the agitator 115 will drop down on the shaft 20, which also serves to carry the agitator out of the way of the operator to some extent. The use of the eccentric 30 accomplishes a smooth action of the mechanism for operating the agitator 120

and prevents any knocking or jerking action in the reversing movement caused in the agitator, and is also found to reduce the power required to drive the agitator, thus enabling a smaller and lower powered motor to be used which is economical in operation, and in the first cost.

By reference to Fig. 5, which shows the specific construction of the eccentric, it will be observed that it comprises two separable portions *a* and *b*, thus permitting the eccentric ring 31 to be placed on the flange *c* of the part *a* and held in position by the part *b*, which is secured to the part *a* by means of bolts or screws passing over openings *d* of the two parts.

By reference to Fig. 1, it will be observed that the wringer 48 is at right angles to the driving shaft 13; that the reciprocating rack-bar and the eccentric are parallel to the wringer, whereby the driving shaft 13 is common to and adapted to drive both the washing and the wringing mechanisms in the manner heretofore described.

Having thus described my invention, what I claim and desire to secure by Letters Patent is:—

1. In a gearing, the combination of a support, a hinged member, a vertical shaft journaled in said member, the lower end of the shaft projecting through the hinged member, a gear attached to the outer end of the shaft, a straight reciprocating rack-bar meshing with said gear, an operating shaft supported independent of said hinged member, and an eccentric on said shaft operatively connected to the rack-bar.

2. In a gearing, the combination of a support, a hinged member, a vertical shaft journaled in said member, a gear attached to the outer end of the shaft, a straight reciprocating rack-bar meshing with said gear, an operating shaft, an eccentric upon the shaft, an eccentric sleeve having a rigid arm projecting therefrom and having its end pivoted to the rack-bar at a point intermediate the ends of said rack-bar.

3. In a gearing, the combination of a support, a hinged member, a vertical shaft journaled in the hinged member, a gear on the outer end of the shaft, a driving shaft supported in a plane above the hinged member, an eccentric on the shaft and opera-

tively connected with said vertical shaft, hinges connecting the hinged member and the support, the pivotal points of the hinges being in a plane above the hinged member and at a point inside of and removed from the said shaft, whereby when the hinged member is raised it swings over and above the shaft and said eccentric for the purpose described.

4. In a gearing, the combination of a support, a hinged member, a vertical shaft supported by the hinged member, a gear attached to the outer end of the shaft, a reciprocating rack-bar meshing with the gear, an eccentric on the shaft, an eccentric sleeve for said eccentric, the sleeve having a rigid arm pivoted to the rack-bar, and hinges connecting the hinged member with the support, whereby the eccentric sleeve revolves around the eccentric to permit the hinged member to be raised.

5. In a gearing, the combination of a stationary member, a member hinged to the stationary member, a driving shaft supported by the stationary member parallel with the pivotal point of said hinge, a vertical shaft carried by said hinged member, a gear of said shaft, a rack-bar meshing with said gear, an eccentric loose on said driving shaft, a sleeve surrounding said eccentric and operatively connected with said rack-bar, and means for locking and unlocking said eccentric with the driving shaft for the purpose described.

6. In a gearing, the combination with a driving shaft, of a support movable in a direction across said shaft, a vertical shaft carried by said support, an eccentric loose on said drive shaft intermediate the ends of said shaft, the eccentric being operatively connected with said vertical shaft, revolute members located at one end of the shaft and extending at right angles thereto, a motor operatively connected to the driving shaft, and means for locking and unlocking the eccentric in respect to the driving shaft for the purpose described.

In testimony whereof I hereunto affix my signature in the presence of two witnesses.

CHARLES J. MARTH.
